(57) **CLAIM**

The ornamental design for a granite and marble nipping tool, as shown and described.

DESCRIPTION

FIG. 1 is a front and left side elevation perspective view taken from above and from the left side of a granite and marble nipping tool showing my new design;

FIG. 2 is a left side elevation view thereof, a right side elevation view being a mirror image thereof;

FIG. 3 is a top plan view thereof;

FIG. 4 is a bottom plan view thereof;

FIG. 5 is a front view thereof; and,

FIG. 6 is a rear view thereof.
